DUAL PRESSURE-RESPONSIVE SAFETY DEVICE FOR PRIME MOVERS

Harry A. Mayor, Fitchburg, and Dana M. Burgess, Leominster, Mass., assignors to General Electric Company, a corporation of New York

Application April 26, 1949, Serial No. 89,646

4 Claims. (Cl. 60—1)

1. This invention relates to a pressure-responsive safety device for shutting down or otherwise modifying the operation of a prime mover in accordance with two pressure conditions appertaining to the operation of the machine, one of which pressures is not to exceed a preselected maximum value, the other of which is not to drop below a preselected minimum value. More specifically, the invention is applicable to a dual pressure-responsive safety device for the governor of a steam turbine having one element responsive to back pressure in the turbine exhaust casing, and a second element responsive to the pressure of the oil used to lubricate the bearings.

As will be understood by those familiar with conventional steam turbine design practice, it is sometimes desirable to provide in the governing system of the turbine some means for preventing steam pressure in the exhaust casing from rising above a preselected value, in order that the mechanical strength of the comparatively large exhaust casing be not exceeded. This exhaust pressure limiting function is also sometimes desired in order to prevent excessive heating of the turbine which may occur with abnormally high back pressures. Likewise, where oil for lubricating the turbine bearings and actuating a hydraulic governor is derived from a pump driven from the turbine shaft, or from some other suitable source, it may be desired to provide a safety device which will act to shut down the turbine in the event the oil pressure falls below a preselected safe value. Heretofore these safety devices have been manufactured as separate components and mounted on the turbine in suitable relation to the governing mechanism.

An object of the present invention is to provide an improved integral safety mechanism incorporating both high exhaust pressure and low oil pressure responsive means acting on a single output shaft connected to the turbine steam admission or trip throttle valve.

Another object of the invention is to provide a dual pressure-responsive safety mechanism of the type described so arranged that during normal operation either of the two safety devices may act to shut down the turbine regardless of the condition of the other device.

Still another object is to provide a very simple compact dual pressure-responsive mechanism which can be manufactured, tested, and installed as a complete integral unit.

Other objects and advantages will be apparent from the following description taken in connection with the accompanying drawing in which

Fig. 1 illustrates diagrammatically a steam turbine incorporating a dual pressure-responsive safety device in accordance with the invention; Fig. 2 is an enlarged view of the safety device, partly in section; Figs. 3, 4 and 5 illustrate the safety mechanism in various conditions of operation; and Fig. 6 is a side view, in elevation of the safety mechanism corresponding to the front view shown in Fig. 2.

10 Referring now more particularly to Fig. 1, the steam turbine shown in general outline form includes hydraulic governing mechanism indicated generally at 1 and arranged to actuate steam valves (not shown) in the inlet casing 2, whence the motive fluid flows into the main turbine casing 3 containing the nozzles and turbine rotor (not shown), thence into the exhaust casing indicated generally at 4 and having the flanged outlet 5. The turbine rotor 6 is supported in suitable bearings in the casings 7, 8, the details of which are not important to an understanding of the present invention. It need only be noted that oil for lubricating these bearings is supplied by branch conduits 9, 10 from a header 11 connected to a suitable pump 12 located in the oil reservoir 13 and arranged to be driven by a shaft and suitable gears (not shown) from the turbine rotor shaft. While it may be of any suitable type, the pump 12 is conveniently of the simple positive displacement gear type. Oil from the reservoir 13 is admitted to the pump 12 through an inlet conduit 14. Since the pump is directly geared to the turbine rotor shaft it will be apparent that the discharge pressure of the pump bears a definite relation to rotor shaft speed. It will be appreciated by those skilled in the art that, in addition to supplying lubricant for the bearings, oil from pump 12 may be supplied to the hydraulic governing mechanism 1, serving as the motive liquid therein.

45 The pressure-responsive safety mechanism which constitutes the specific subject matter of the present invention is indicated in Fig. 1 generally at 15, being shown as mounted directly on the side of the hydraulic governing mechanism 1. The precise nature and mechanical details of the turbine governing mechanism 1 are not necessary in understanding the present invention. Typical governing systems including a rotatable trip shaft 50 analogous to shaft 16 are disclosed in U. S. Patents 2,188,187, issued January 23, 1940, on an application of P. H. Knowlton, also 2,027,848, issued January 14, 1936, on an application of D. F. Warner, and 2,294,753, issued September 1, 55 1942, on an application of S. N. Hedman. It need

only be noted here that a "trip shaft" 16 (Figs. 2 and 6) projects into the governing mechanism 1 and is provided with suitable latch surfaces 16a formed by machining diametrically opposed flat surfaces on the rod 16. As will be seen hereinafter, this trip shaft has a normal running position and an emergency tripped position, rotation of the shaft from one to the other causing the latch portion 16a to trip the governor 1 to the inoperative position, or perform some other function to modify the operation of the governing system.

As will also be seen from Figs. 2 and 6, the trip shaft 16 is journaled in a plate 17 which serves as the main frame member supporting the various components of the safety device on the casing of the governing mechanism 1. It will of course be understood that the frame plate 17 is secured by suitable threaded fastenings 18 to the governor housing. Carried on trip shaft 16 at the exterior side of frame plate 17 is a first lever member 19 arranged to oscillate through a limited arc, the extreme clockwise position being determined by a stop pin 20 fixed to the frame plate 17. A suitable coil spring 21 is connected to a fixed pin 21a at one end, the other end being connected to a transverse pin 22 extending entirely through the lever 19. Spring 21 is arranged to bias the lever 19 lightly upward in the counterclockwise direction about trip shaft 16. It is to be noted that this spring is just sufficiently strong to counterbalance the weight of lever 19 and overcome the friction in the respective parts so that lever 19 will return to its counterclockwise position when permitted to do so by the other components of the system.

Secured to the depending lower portion of frame plate 17 is a casing 23 containing two pressure-responsive pistons 24, 25. Piston 24 is carried on a rod 26 slidably projecting through a bushing formed by a cylindrical nut 27 threadedly received in an opening in the top of casing 23. Similarly piston 25 is carried on rod 28 slidably projecting through a cylindrical bushing nut 29. The pistons are strongly biased to their lowermost positions by a pair of comparatively heavy coil springs 30, 31 the upper ends of which engage the under surfaces of the respective nuts 27, 29. It will be obvious from consideration of Fig. 2 that the compressive force exerted by the springs 30, 31 may be readily adjusted by applying a suitable spanner wrench and turning the nuts 27, 29 so as to move them longitudinally in the threaded recesses in the casing top member 23a. As will be seen more particularly hereinafter, the uppermost position of the pistons is determined by engagement with the top casing member 23a. The lowermost position of piston 24 is defined by a cylindrical abutment or "stop tube" 32, which may be conveniently formed integral with a fitting 33 defining a nipple for receiving a threaded pipe coupling at 33a and a nut 33b for securing the fitting to the bottom casing plate 23b. The lowermost position of piston 25 is determined by the interconnection of piston rod 28 with the linkage described hereinafter.

As will be obvious from Fig. 2, the respective pistons 24, 25 are sealed to flexible Sylphon bellows 34, 35 forming expansible pressure-responsive chambers. The other end of bellows 34 is silver soldered or otherwise secured to a circumferential flange formed on the fitting 33. The bottom of the other bellows 35 is likewise secured to the flange of a similar fitting 36.

As will be apparent from Fig. 1, the steam pressure obtaining in the exhaust casing 4 is transmitted by way of pressure transmitting pipe 37 to the fitting 33 so that the exhaust casing pressure is communicated through the bore of fitting 33 and a plurality of radial holes 32a to the chamber defined within bellows 34 and the bottom surface of piston 24. Likewise, the pressure of the oil discharged from pump 12 is communicated by a pressure line 38 connected to the fitting 36 so that the bellows 35 is responsive to oil pump discharge pressure.

The pressure-responsive pistons are connected to the trip shaft 16 by a special linkage, as follows. Piston rod 26 is connected by a pivot 39 to a link 40 having at its other end an elongated slot 41 in which slides a pivot pin 42 fixed to the lefthand end of the trip shaft 19. Similarly, piston rod 28 is pivoted at 43 to a link 44 having a slot 45 in which slides the exterior end of the pin 22 fixed in the lever 19.

A second latch lever 46 is supported on the frame plate 17 by means of a fixed fulcrum pin 47. At its lefthand end, latch lever 46 is connected by a pin and slot arrangement to the link 40, and at its righthand end it carries a spring-biased latch or detent 48. As may be seen in Fig. 6, detent 48 pivots in a slot in the end of latch lever 46 on a stud 49 fixed to the latch lever 46. A coil spring 49a disposed around stud 49 has a remote end engaging a flange on the end of stud 49, the other end engaging the latch 48 so as to bias it in the clockwise direction as viewed in Fig. 2. The extreme clockwise position of detent 48 relative to latch lever 46 is determined by a small laterally projecting "ear" 48a adapted to engage adjacent portions of the lever 46. The extreme tip of detent 48 is shaped to engage a cooperating notch 50 formed in the lower edge of the trip lever 19.

The method of operation of this improved safety device may be seen by reference to Figs. 2-5.

Fig. 2 represents the "shut-down" or inoperative condition of the powerplant, with both pressure-responsive pistons 24, 25 in their lowermost positions. It will be seen that the piston 24 is engaging the stop tube 32, while the lowermost position of piston 25 is determined by the engagement of the slotted link 44 with the pin 22, the position of which is determined by the stop pin 20 engaging the lever 19. In this connection it may be noted that the comparatively stiff coil spring 31 overcomes the comparatively lighter resistance of coil spring 21, so that piston 25 is strongly biased to its lowermost position as determined by stop pin 20 whenever the oil pressure supplied to bellows 35 falls below the preselected value. It will be seen from Fig. 2 that, in the inactive condition, the pivot pins 42 and 22 are both at the extreme upper portions of the respective slots 41, 45, and that the detent 48 is in the disengaged position relative to lever 19 and in its extreme clockwise position relative to lever 46. When shut down, there is of course no fluid pressure in either of the bellows 34, 35, atmospheric pressure prevailing throughout the system.

Suppose now it is desired to start the turbine. It is first necessary to put the turbine governor 1 in condition to permit operation by manually lifting the trip lever 19 to the counter-clockwise position shown in Fig. 3. It will be observed that the extreme counterclockwise position of lever

19 is determined by the engagement of pivot pin 42 with the lower end of slot 41. It will be seen in Fig. 3 that pin 42 is almost but not quite at the bottom of slot 41. It will also be observed that this counterclockwise movement of trip lever 19 causes the oil pressure piston 25 to be pulled almost, but not quite, to the extreme uppermost limit of its range of movement. Now with the trip lever 19 manually held in its uppermost position, the detent 48 is manually rotated 10 counter-clockwise against the bias of its coil spring 49a so that the tip of the detent engages the notch 50 in lever 19. It will be observed that the slight clockwise rotation of trip lever 19 as the end of detent 48 drops into the notch 50 accounts for the slight clearance between pivot pin 42 and the bottom end of slot 41 in link 40. This slight clearance is significant for a reason noted hereinafter. With detent 48 engaging the trip lever 19, the latter is held in the position corresponding to the normal running condition of the governor 1, against the strong downward bias of coil spring 31 associated with the oil pressure piston 25. The governing mechanism 1 is now in such condition that steam can be supplied to the turbine rotor. As the rotor speed increases, in accordance with the operation of the steam inlet valves controlled by the hydraulic governor 1, the rotational speed of the oil pump 12 also increases, with the result that oil pressure builds up in the bellows 35. Eventually, the oil pressure becomes sufficient to move piston 25 upwardly until it engages the underside of casing top member 23a as shown in Fig. 4. This small additional increment of upward movement, beyond the position of piston 25 illustrated in Fig. 3, permits the light biasing spring 21 to rotate lever 19 slightly counterclockwise, this movement being permitted by the aforementioned clearance between pivot pin 42 and slot 41 illustrated in Fig. 3. This small movement of trip lever 19 causes the detent 48 to be disengaged from notch 50, with the result that coil spring 49a snaps the detent 48 to its extreme clockwise position, represented in Fig. 4.

Throughout the above-described process, the back-pressure piston 24 has remained in its lowermost position, seated against the end of stop tube 32. The mechanism is now in the normal running condition, with trip lever 19 in its counterclockwise position, the back-pressure piston 24 in its lowermost position and the oil pressure piston 25 "floating" in its uppermost position, being supported by the oil pressure in bellows 35.

Assume now that for some reason the steam pressure in the exhaust casing 4 should increase to a dangerously high level, for instance, a pressure on the order of 10 lbs. per square inch gage. This pressure, communicated to bellows 34 through the pressure sensing conduit causes the back-pressure piston to rise against the bias of spring 30. Since in the normal running condition represented by Fig. 4 the pivot pin 42 was at the bottom of slot 41, this upward movement of piston 24 immediately effects clockwise rotation of the trip lever 19. As noted above, rotation of lever 19 to the extreme clockwise position against stop pin 20 causes the latch portions 16a of the trip shaft 16 to effect shutting down of the turbine. Of course, the turbine trip mechanism may be so arranged that rotation of the lever 19 all the way to the stop pin 20 may not be needed. The degree of movement of trip lever 19 required to shut down the turbine will of course depend upon the nature and arrange-

ment of the governor 1. With the governor thus disabled and the flow of motive fluid to the turbine discontinued, the rotor speed will of course drop, and the oil pressure decreases proportionally. At pressures below a preselected critical value, for instance 4 lbs. per square inch, the oil pressure piston 25 again descends to its lowermost position. The discontinuance of the steam supply will of course decrease the back pressure acting on piston 24 so that it also descends to its lowermost position against stop tube 32. Thus both pistons and the interconnecting linkage are restored to the inactive condition represented by Fig. 2.

If on the other hand during operation the oil pressure should fail for some reason, as for instance through failure of the pump 12 or breakage of one of the hydraulic lines, the decrease in oil pressure below the preselected critical value will permit the oil pressure piston 25 to descend from the position shown in Fig. 4. This will of course cause clockwise rotation of the trip lever 19 so that the governor 1 is again disabled and the turbine shut down.

It will be observed from the above that regardless of whether the turbine is shut down by high back pressure or low oil pressure, the resulting decrease in oil pressure acting on the piston 25 when the machine is shut down will insure that the linkage will be restored to the inactive condition represented in Fig. 2. It will also be noted that the arrangement of the slots in the links 40, 44 is such that, when in the running condition, either of the pressure-responsive pistons is completely free to move the trip lever 19 in the clockwise direction to shut down the turbine regardless of the position of the other piston. Thus each of the safety devices incorporated in the present invention is free during normal operation to perform its function completely independent of the other safety device. At the same time, the present arrangement provides a very neat compact combination occupying a minimum of space, and having a minimum number of parts required to correlate the operation of the two safety devices with each other and the governor trip shaft.

It will also be seen that the critical pressures for which the devices are set may be readily adjusted by means of the nuts 27, 29 by varying the compression forces of the springs 30, 31.

An additional feature which may be noted is that during the starting cycle, when the detent 48 is holding the lever 19 in the normal running condition (Fig. 3), any accidental increase of pressure in exhaust casing 4, for instance due to the operator's error in failing to open a valve in the exhaust pipeline connected to the discharge opening 5, will move the back-pressure piston 24 upwardly, with the result that pin 46a causes the latch lever 46 to rotate slightly in a clockwise direction about its fulcrum 47. This movement causes the detent 48 to disengage the notch 50 in lever 19, so that detent 48 snaps to its clockwise position shown in Fig. 4 leaving the back-pressure piston 24 free to move trip lever 19 clockwise to shut down the turbine as described above.

It will thus be seen that this improved safety device combines in one simple mechanism two pressure-responsive devices, one for insuring that a first pressure condition in the powerplant does not rise above a preselected value, while the other insures that a second pressure condition will not fall below another preselected critical value, both pistons being connected by a specially arranged common linkage system to the trip lever of the

turbine governing system in such a manner that either pressure-responsive piston is at all times free to move the trip lever to shut down the turbine, a special latch arrangement being provided to support one of the pistons in the operative condition during the starting cycle when one of the pressure conditions is below its minimum value. Thus, two valuable safety devices heretofore constructed as separate mechanisms are conveniently and effectively combined into a single integrated unit.

It will be obvious from the above description that many modifications might be made in the nature of the pressure-responsive devices used and the mechanical details of the linkage interconnecting them with the turbine trip lever, and it is desired to cover by the appended claims all such changes and modifications as fall within the true spirit and scope of the invention.

What we claim as new and desire to secure by Letters Patent of the United States is:

1. In a dual pressure-responsive control device for a machine in which a first fluid pressure condition is not to exceed a first preselected maximum value and a second fluid pressure condition is not to drop below a second preselected minimum value, the combination of a trip lever member pivotally supported at an intermediate point for oscillation through a limited arc from a normal running position to an emergency tripped position, spring means lightly biasing the trip lever to one extreme position representing the normal running condition of the machine, first fluid pressure motor means including a first actuating member with means biasing it to one extreme position and walls defining an expandable chamber adapted to move said actuating member against its biasing means in accordance with values of the first pressure condition exceeding said preselected maximum value, second fluid pressure motor means including a second actuating member with means strongly biasing it to an extreme position corresponding to an emergency tripped position of the lever, and walls defining an expandable chamber adapted to hold said second actuating member in normal running position against its biasing means in accordance with the second fluid pressure condition, a first lost motion connection between the first actuating member and the trip lever adapted to effect rotation of the trip lever to the emergency position upon increase of the first pressure condition above said preselected value, a second lost motion connection between the second actuating member and the trip lever adapted to effect rotation of the trip lever to the emergency position upon decrease of the second pressure condition below said second preselected value, a latch lever fulcrumed at an intermediate point and pivotally connected at one end to said first actuating member, a detent pivoted to the other end of the latch lever and having a portion adapted to hold the trip lever and second actuating member in normal running position when the trip lever is manually moved to said position and the detent manually caused to engage the lever, means biasing the detent out of engagement with the trip lever when the second fluid pressure condition rises above said second preselected value, each of said lost motion connections being adapted to permit free movement of the trip lever relative to the associated actuating member in the event the lever is moved to the emergency position by the other actuating member.

2. In a dual pressure-responsive control device

for apparatus in which a first fluid pressure condition is not to exceed a first preselected maximum value and a second fluid pressure condition is not to drop below a second preselected minimum value during normal operation, the combination of first and second fluid pressure-responsive means each having a member adapted to reciprocate in transversely spaced substantially parallel paths in accordance with changes in said respective pressure conditions, stop means positively limiting the movement of both members in the increase pressure direction, stop means positively limiting the movement of the first pressure responsive member in the decrease pressure direction, a trip lever member pivotally supported on a fixed fulcrum located between said paths and adapted to oscillate through a limited arc from a normal operating position to an emergency tripped position, first and second lost motion means connecting the pressure responsive members to the trip lever at opposite sides of said fulcrum, means lightly biasing the trip lever to the normal running position, means strongly biasing the respective pressure-responsive members to their minimum pressure positions, and a latch lever member pivotally supported on a fixed fulcrum located between the pressure responsive members, one end of the latch lever being connected to the first pressure responsive member and the other end carrying a pivoted detent adapted to engage the trip lever to hold it latched in the normal operating position with the second pressure responsive member in substantially the maximum pressure position when the second pressure condition is below said preselected minimum value, and means biasing said detent to disengaged position relative to the trip lever, whereby either movement of the first pressure responsive member in the increase pressure direction or slight movement of the second pressure responsive member from the latched position in the increase pressure direction effects disengagement of said detent from the trip lever thereby rendering it free to move to the emergency tripped position in accordance with movement of the first pressure responsive member in the increase pressure direction or of the second pressure responsive member in the decrease pressure direction.

3. In a dual pressure-responsive safety device for an elastic fluid turbine in which the exhaust casing pressure is not to exceed a first preselected maximum value and the pressure of the oil supplied to the turbine bearings and governor is not to drop below a second preselected minimum value during normal operation, the combination of first fluid pressure responsive means having a member positioned linearly in accordance with exhaust casing pressure, second fluid pressure responsive means having a member adapted to reciprocate in a path parallel to and transversely spaced from the path of movement of said first pressure-responsive member in accordance with changes in oil supply pressure, stop means positively limiting the movement of both pressure-responsive members in the increase pressure direction, stop means positively limiting the movement of the back pressure-responsive member in the decrease pressure direction, a trip lever adapted to modify the action of the turbine governor and pivotally supported on a fixed fulcrum located between the paths of movement of said pressure responsive members and adapted to oscillate through a limited arc from a normal operating position to an emergency tripped po-

sition, first lost motion means connecting the back pressure responsive member to one end of the trip lever, second lost motion means connecting the oil pressure responsive member to the trip lever at the opposite side of said fixed fulcrum, means lightly biasing the trip lever to the normal running position, means strongly biasing the pressure-responsive members to their respective minimum pressure positions, and a latch lever member pivotally supported on a fixed fulcrum located between the pressure-responsive members, means pivotally connecting one end of said latch lever to said first pressure-responsive member, a detent pivotally carried on the other end of the latch lever and adapted to engage the trip lever to hold it latched in the normal operating position during the starting cycle when oil pressure is below the preselected minimum value, and means biasing said detent to disengaged position relative to the trip lever, whereby either movement of the back-pressure responsive member from its minimum pressure stop or movement of the oil pressure responsive member to its maximum pressure position effects disengagement of the detent from the trip lever thereby rendering the latter free to move to the emergency position in accordance with either an increase in turbine back pressure above the preselected maximum value or a decrease in turbine oil pressure below the preselected minimum value.

4. In a combined high back pressure and low oil pressure safety device for an elastic fluid turbine, the combination of first fluid pressure responsive means having a member adapted to be positioned linearly in accordance with increases in turbine back pressure above a preselected maximum value, second pressure-responsive means including a member adapted to be positioned in a linear path substantially parallel to that of the first member in accordance with turbine oil pressure, stop means positively limiting

the movement of both pressure responsive members in the maximum pressure direction, stop means positively limiting the movement of the back pressure responsive member in the minimum pressure direction, a pivoted trip lever adapted to oscillate through a limited arc from a normal running position to an emergency tripped position, means connecting said pressure-responsive members to the trip lever and adapted to independently effect oscillation thereof from the normal running position to the emergency tripped position, first means lightly biasing the trip lever to the normal running position, means strongly biasing the respective pressure-responsive members to their minimum pressure positions, and a pivoted latch member connected at one end to the back pressure-responsive member and carrying at the other end a pivoted detent adapted to hold the trip lever latched in the normal operating position with the oil pressure-responsive member in substantially the maximum pressure position when oil pressure is below the preselected minimum value, means biasing said detent to disengaged position relative to the trip lever, the connecting means between the back pressure-responsive member and the trip lever being adapted to permit slight relative movement therebetween when the oil pressure-responsive member moves from the latched position in the increase pressure direction, whereby said first biasing means effects relative movement between said trip lever and latch lever to disengage the detent and render the trip lever free to move to the emergency tripped position in accordance with either movement of the back pressure-responsive member in the increase pressure direction or movement of the oil pressure-responsive member in the decrease pressure direction.
